ABSTRACT: A display panel includes a first plate having slots for receiving anode electrodes and a surface for supporting cathode electrodes for operation with said anode electrodes. A cover plate covers the electrode assembly, with gas-filled spaces being provided, above each cathode, in which cathode glow can be generated facing a viewer. The anode electrodes are hidden from view and do not obstruct the cathode glow. The slots can also be used to provide communication of excited particles between adjacent anodes to facilitate the firing of adjacent cells.

COMPACT DISPLAY PANEL

BACKGROUND OF THE INVENTION

Various types of display panels comprising a plurality of gas-filled cells which can be turned on selectively to display a message are known in the art. In a recent development of Holz and Ogle, a display panel has been devised which has two layers of cells, a first layer being used as a scanning or addressing layer for sequentially addressing the cells, and a second layer in which information is inserted to be displayed, and perhaps stored, as the first layer is scanned. These multilayer devices have been constructed of at least four layers of glass or other insulating material with electrodes suitably positioned between them, at least two of the layers containing a matrix of closely spaced apertures which serve as gas cells. Although these devices have been built and operated successfully, there is a need to provide economies by eliminating component parts, such as one or both of the apertured glass plates. The present invention provides such economies and achieves the effect of four layers or plates with but two plates.

SUMMARY OF THE INVENTION

Briefly, a display panel embodying the invention includes an arrangement of plates and cathode glow electrodes and anode electrodes such that cathode surfaces are available to glow and face the viewer with no obstruction to viewing therebetween. The panel also includes favorably disposed drift spaces for excited particles to flow from scanning cells to display cells in one mode of operation.

DESCRIPTION OF THE DRAWINGS

FIG. 1 is a perspective view of a display panel embodying the invention;

FIG. 2 is a sectional view along the lines 2—2 in FIG. 1;

FIG. 3 is a sectional view along the lines 3—3 in FIG. 1;

FIG. 4 is a sectional view along the lines 4—4 in FIG. 1;

FIG. 5 is a sectional view along the lines 5—5 in FIG. 1;

FIG. 6 is perspective view of a portion of the bottom surface of our cover plate of the panel of FIG. 1 and portions of associated electrodes, the view illustrating one form of a portion of the panel;

FIG. 7 is a view similar to that of FIG. 6 showing a modification of a portion of the panel;

FIG. 8 is a sectional, elevational view of a portion of a panel showing another modification of a portion of the panel of FIG. 1;

FIG. 9 is a perspective view of a portion of a panel showing another modification of the invention;

FIG. 10 is a perspective view of a portion of a panel showing another modification;

FIG. 11 is a sectional, elevational view of a panel showing another modification of the invention;

FIG. 12 is a plan view of a portion of the panel of FIG. 11;

FIG. 13 is a plan view of a panel showing a modification of a portion of the invention; and

FIG. 14 is a sectional elevational view of another modification of the invention.

FIG. 15 is a sectional elevational view of a modification of a portion of the invention;

FIG. 16 is a perspective view of another modification of a portion of the invention;

FIG. 17 is a sectional view, along the lines 17—17, in FIG. 16; and

FIG. 18 is a sectional view, along the lines 18—18, in FIG. 16.

DESCRIPTION OF THE PREFERRED EMBODIMENTS

The display panel shown in the drawings and described below includes relatively few display cells; however, it is to be understood that the panel may be made in almost any size and with almost any number of display cells.

Display panel 10 embodying the invention includes a lower plate 20 of glass, ceramic, or the like, and preferably opaque to prevent light crosstalk, having a top surface 30 and a bottom surface 40. Plate 20 is provided with a plurality of first parallel slots 50 which alternate with second parallel slots 56, the slots being shown as having a rectangular cross section, but they may have any suitable cross section, and they may or may not be identical in shape and size. The slots 50 and 56 extend a suitable distance from the top surface 30 toward the bottom surface 40 of plate 20. In panel 10 and for purposes of later description of one mode of operation, slots 50 are defined as display slots, and slots 56 are defined as counting slots.

An electrode 60, operable as a display anode, is disposed in each slot 50, and an electrode 66, operable as a counting or scanning anode, is disposed in each slot 56. Electrodes 60 and 66 may be separate wires, flat strips, or the like, which are set into their slots, or they may be films or coatings plated or evaporated into their slots. The electrodes 60 and 66, if they are separate wires or strips, may also be secured in place by means of a cement such as a glass frit or the like (not shown) placed at the ends of the electrodes and their slots or at any suitable location. The electrodes may also be held in place by the seal between the various parts of the panel (to be described).

A plurality of electrodes 70, operable as cathode electrodes and preferably in the form of flat strips having top surfaces 71 and bottom surfaces 72, are disposed on the top surface 30 of plate 20 and oriented, preferably, at a 90° angle to the parallel anode electrodes 60 and 66. Each cathode electrode 70 crosses each of the anode electrodes, and each such crossing defines a gas cell, with the cells associated with the display anodes being display cells 74, and those associated with the counting or scanning anodes being counting or scanning cells 76. Cells 76 are also known as priming cells since, in one mode of operation, they provide excited particles which prime and facilitate the firing of display cells 74.

The panel 10 is completed by a cover or viewing plate 80, which has a top surface 90 and a bottom surface 100, (FIGS. 1 and 2) which is sealed gastight to the bottom plate 20 by means of a suitable cement such as a glass frit or the like 102 secured to the edges of the top and bottom plates.

According to the invention, the top plate 80 and/or the associated electrodes 70 are constructed so that gas-filled viewing spaces or viewing cells 110 are provided above selected portions of the top surfaces 71 of each of the cathode electrodes 70. These spaces may be provided by means of parallel slots or depressions 112 which are formed in the bottom surface of the top plate and extend along the length thereof transverse to the cathodes 70 (FIGS. 1 to 6). The desired arrangement may also be provided by fusing strips of glass frit or the like 114 to the bottom surface of the top plate so that the depressions 112 are provided between them, as shown in FIG. 7.

Since the cover plate 80 rests on the cathodes 70, spaces 120 are provided between the bottom surface 100 of cover plate 80 and the top surface of baseplate 20. Preferably, all of these striplike portions of the bottom surface 100 (thus, in effect, all of the bottom surface of plate 80) are blackened to render them opaque. In FIG. 7, the glass frit strips 114 are made with a black glass frit which can be purchased commercially. The black areas in the other FIGS. can be made of a thin film of a black glass frit or with any suitable inorganic substance which will not interfere with the operation of the panel and its gas.

The spaces or display cells 110 can also be provided by properly shaping the cathode strips 70. For example, as shown in FIG. 8, if the cathodes have raised areas 116 spaced apart along their lengths, this has the effect of providing spaces 110 between the bottom surface of the top plate 80 and the portions 117 of the cathodes between the elevations 116.

For one mode of operation of panel 10, the spaces 110 which extend along the entire length of the panel, are pro-

vided for, and aligned with, each display anode 60, with the black areas of surface 100 being provided for, and aligned with, each scanning anode 66. The spaces or display cells 110 are of such width that each overlays its associated display slot 50 with which it is aligned and extends into the space between adjacent slots 56. The display spaces 110 may extend up to the slots 56 on either side of a display slot 50.

It can be seen that the black areas of surface 100 overlaying counting or scanning slots 56 prevent light generated therein from being seen by a viewer looking through the top or viewing plate 80.

The panel 10 includes a suitable ionizable gas or mixture of gases selected from the group consisting of argon, neon, xenon, krypton, etc., and a small quantity of mercury is usually added to the gas to minimize cathode sputtering. The gas is introduced by means of a tubulation (not shown) secured to one of the plates 20 or 80, or it is introduced in any other suitable manner.

As noted above, each crossing of a cathode 70 and a counting node 66 defines a counting cell 76, so that each cathode forms a column of counting cells. Thus, beginning at the left in FIG. 1, there are cathodes 70A, 70B, 70C, etc. depending on how many columns of cells are provided. Similarly, each crossing of a cathode and a display anode defines a column of display cells 74. In panel 10, each column of cells includes display cells 74 and counting cells 76 aligned in common columns with display cells and counting cells alternating with each other in a common column.

Panel 10 may be operated in different ways, some of which will be described in different degrees of detail. In one mode of operation, the first cathode 70A, associated with the first column of cells, at the left end of panel 10, is connected to ground or other generally negative potential, and all of the counting anodes 66 are connected to a source of positive potential such that a firing potential appears across each counting cell 76 formed by these anodes and the first cathode 70A. The first column of counting or scanning cells 76 now fires and glows; however, this glow is not visible through the black areas of surface 100 of cover plate 80 which cover these cells. With cells 76 ON, excited particles generated thereby, particularly metastable atoms, flow out of slots 56 through the spaces between adjacent cathodes 70 into the adjacent display slots 50 and into the spaces or display cells 110 above the cathodes 70.

If now, as the counting cells 76 in the first column are turned on, signal information, in the form of a positive voltage, is applied to one or more of the display anodes 60, then the display cells 74 in the first column, which include these energized anodes, fire and glow. This firing operation is facilitated by the priming action of the excited particles present in these cells. The glow thus generated in the cells 74 starts below the cathodes 70 and spreads to the top surface of the cathodes 70 in the spaces or display cells 110 and is visible to a viewer.

If now, signals representing information to be displayed are applied to the anodes 60 of the display cells 74 which have been turned on, the current flow therethrough can be modulated to provide a corresponding level of intensity of glow in the cells 74. This modulation can be achieved by modulation of the current amplitude or by modulation of the pulse width of the applied information signal.

The above-described operation is repeated for the second column of cells by the removal of turn on potential from the first cathode 70A and the application thereof to the second cathode 70B associated with the second column of counting or priming cells 76 and display cells 74. Selected anodes again are energized as described above to turn on and provide properly modulated glow in selected associated display cells 74. This mode of operation is carried out cyclically, with each of the cathodes and the proper anodes being energized in turn and at such a rate that a stationary but changeable message or character can be displayed by the panel and visible through plate 80.

In a modification of the invention shown in FIG. 9, each cathode strip 70 is provided with slots 140 along its length, each of which extends across a display slot 50 and across the adjacent solid portion of plate 20 to overlay a portion of the adjacent counting slot 56. Such slots 140 facilitate communication between the counting cells 76 and the adjacent display 15 cells 74 by providing a more direct path for the flow of excited articles from an ON counting cell to a display cell to be turned on. Thus, for example, if the counting cells 76 associated with a cathode 70A and anodes 66 are ON and exhibiting glow and a display anode 60A receives an information signal, then, with excited particles present due to flow from the adjacent cell through cathode slot 140A to the associated display cell 110A, turn on of cell 110A above cathode 70A is facilitated.

If desired, the slots 140 may be extended to the ends of the cathodes, as illustrated briefly in FIG. 10, so that each cathode is actually now made up of two narrower cathode strips 70'.

In still another modification of the invention shown in FIGS. 11 and 12, the necessary communication paths comparable to slots 140 are provided as narrow elongated depressions 180 formed in the bottom surface of each cathode and extending between counting slots 56 and display slots 50, as desired. Communication might also be provided by means of slots 170 cut into the top surface of plate 20, with or without cathode depressions 180.

In order to control the diffusion or spread of glow from counting cells, it may be necessary to set the cathodes, in FIGS. 11 and 12 or in any of the other structures, into the bottom surface of cover plate 80 or into the top surface of lower plate 20.

As shown in FIG. 13, in any pertinent embodiment of the invention, the cathode slots 140 might extend between a counting slot 56 and both adjacent display slots 50 so that one counting slot could operate with two adjacent display slots.

The display panel described herein may also be modified to utilize every slot and every cathode portion associated with it as a display cell. Such a panel shown in FIG. 14 includes bottom plate 20 with identical slots in which anode wires 220 are seated. The bottom plate thus may be identical in construction to the same plate shown in FIG. 1. The cathode electrodes 70 are provided as above; however, the top plate is modified to provide display spaces 110 extending along and overlying each slot. In this type of panel, when operating potential is applied to each anode and each cathode, cathode glow will originate at the bottom surface of the energized cathode and will spread to the space 110 above the associated cathode portion 117.

In the modification of the invention shown in FIG. 15, the display cells 110 are extended so that they are close to, or even slightly overlap, the counting slots 56. With this arrangement, the flow path for excited particles, from a counting cell to a display slot 50 and display cell 110, is shortened.

In another modification of the invention shown in FIGS. 16 to 18, the top surface of bottom plate 20 is provided with slots 212 (one shown) which lie under the cathode strips 70 and are concealed thereby. The cathode strips are provided with small apertures 214 (one shown) disposed along their lengths and positioned between a lower counting slot 56 and a lower display slot 50 but beneath an upper display cell 110. The apertures 214 are small enough so that glow from a counting cell in plate 20 cannot enter a display cell 110, but they are large enough so that excited particles in the glow can prime a display cell and prepare it for firing when firing potentials are applied.

In the various embodiments of the invention illustrated, the exact sizes and spacing of the various parts have not been shown with dimensional exactness. Although the theory of operation of gas discharge devices may not always be well-known, and this is particularly true of new devices of the type described herein, presently known theory seems to suggest that spacings of parts and dimensions of spaces between parts in the vicinity of counting cells formed in the lower plate of 75 the devices should be such that small quantities of excited par-

ticles can diffuse to the vicinity of adjacent display areas for priming purposes, but no considerable glow mass should be able to diffuse and spread from cathode areas used for counting glow to cathode areas used for display. In general, an aperture of 1 to 3 mils is the proper size to present spurious spreading.

What is claimed is:

1. A display panel including

a gas-filled envelope comprising a first insulating baseplate and a transparent cover plate,
said first plate having a top surface and a bottom surface and having a plurality of parallel slots extending from said top surface downwardly toward said bottom surface,
first electrodes in one group of said slots and second electrodes in another group of said slots with first and second electrodes alternating with each other in alternate slots,
said first electrodes being designated counting electrodes and said second electrodes being designated display electrodes, and

a plurality of third electrodes disposed on said top surface of said first plate and oriented perpendicular to said first and second electrodes,

each third electrode crossing a portion of each first and second electrode, each crossing of a third electrode and a first electrode defining a counting cell, and each crossing of a third electrode and a second electrode defining a display cell,

said cover plate being spaced from each portion of each third electrode which is associated with a display cell to provide a display space in which gas glow can be viewed through said cover plate,

there being a particle flow space extending from each counting cell to an adjacent display cell and to said display space associated therewith.

2. The panel defined in claim 1 and including opaque areas obstructing viewing of said counting cells through said cover plate.

3. The panel defined in claim 1 wherein said cover plate has a top surface and a bottom surface, and opaque areas are provided on said bottom surface of said cover plate to shield selected ones of said cells from view through said cover plate.

4. The panel defined in claim 3 wherein said bottom surface of said cover plate is provided with depressions which form said display spaces above each said third electrode.

5. The panel defined in claim 3 wherein said bottom surface of said cover plate has layers of insulating material secured to it to form each said display space between them.

6. The panel defined in claim 3 wherein said first plate is of an opaque insulating material to minimize light crosstalk between said gas-filled cells when said cells glow.

7. A display panel including

a gas-filled envelope consisting of a first insulating baseplate and a second insulating cover viewing plate,
means forming a plurality of gas-filled cells in a common layer in said envelope,
an anode electrode and a glow cathode electrode associated with each cell, the anode electrode being positioned within said baseplate and said cathode being positioned in contact with said baseplate adjacent to said cover plate, each cathode being in operative relation with at least two of said cells and with the anode electrodes therein, each cathode including a slot providing gas communication between said two cells.

8. The panel defined in claim 7 and including means concealing at least one of said cells from view so that, when said one cell glows, the glow cannot be seen but excited particles generated by the glow can flow through said slot in said cathode to the other cell to prime said other cell for subsequent firing.

9. The panel defined in claim 8 wherein said cover plate is in contact with a portion of said cathode which overlays said one cell and is spaced from the portion of said cathode which overlays said other cell, the space provided thereby being a glow

display space which presents unobstructed display to a viewer looking through said cover plate.

10. A display panel including

a gas-filled envelope comprising a first insulating baseplate and an insulating top cover viewing plate,
said first base plate having a top surface and a bottom surface with said top viewing plate sealed thereto in gastight engagement, said top plate having a top surface and a bottom surface,

a plurality of parallel slots in said first plate, first electrodes seated in said slots remote from said top surface of said first plate,

second electrodes seated on said top surface of said first plate and oriented parallel to each other but at an angle to said first electrodes whereby each second electrode crosses each of said first electrodes and each crossing forms a gas-filled cell including a portion of a first electrode and a portion of a second electrode as the electrodes for the cell,

said top plate being seated on portions of said second electrodes,

said top plate being spaced from other portions of said second electrodes whereby a gas-filled display space is provided between said other portions of said second electrodes and said cover plate, there being a gas communication path extending from each said first electrode through its said slot and between adjacent second electrodes into an adjacent slot and into the said gas-filled space above the portion of said second electrode associated with said adjacent slot.

11. The panel defined in claim 10 and including means obstructing viewing of selected ones of said cells through said top plate.

12. The panel defined in claim 10 and including opaque areas provided on said bottom surface of said top plate to shield selected ones of said cells from view through said top plate.

13. The panel defined in claim 12 wherein said bottom surface of said top plate is provided with depressions which form said display spaces above each said second electrode.

14. The panel defined in claim 12 wherein said bottom surface of said top plate has layers of insulating material secured to it to form each said display space between them,

there being particle flow space extending from each counting cell to an adjacent display cell and to said display space associated therewith.

15. The panel defined in claim 1 and including means concealing said counting cells from view so that, when each said counting cell glows, the glow cannot be seen by a viewer but excited particles generated by the glow can flow through said particle flow space to adjacent display cells to prime said display cells for subsequent firing.

16. The panel defined in claim 1 wherein said third electrode includes slots which extend from a counting cell to an adjacent display cell.

17. The panel defined in claim 16 and including means concealing said counting cells from view so that, when a counting cell glows, the glow cannot be seen by a viewer but excited particles generated by the flow can flow through one of said slots in said third electrode to an adjacent display cell to prime said display cell for subsequent firing.

18. The panel defined in claim 16 wherein said slots extend along the entire length of each third electrode so that in effect each third electrode comprises two narrow spaced-apart electrode portions.

19. The panel defined in claim 1 wherein each third electrode has bottom surface provided with depressions providing communication paths between adjacent first and second slots.

20. The panel defined in claim 1 wherein said third electrodes include apertures providing direct communication between selected ones of said slots and the space above said third electrodes.
